(57) **CLAIM**

The ornamental design for a pipette barrel, as shown and described.

DESCRIPTION

FIG. 1 is a front view of a first embodiment of a pipette barrel showing my new design;

FIG. 2 is perspective view of the design of FIG. 1;

FIG. 3 is a front view of a second embodiment of a pipette barrel showing my new design; and,

FIG. 4 is a perspective view of the design of FIG. 2;

The broken lines in the Figures are included for the purpose of illustrating portions of the pipette barrel that form no part of the claimed design.

1 Claim, 4 Drawing Sheets
